United States Patent Office.

DEDRICK JORDAN, OF CHARLESTOWN, MASSACHUSETTS.

Letters Patent No. 64,227, dated April 30, 1867.

IMPROVED CUTTER-GUIDE FOR MOULDING MACHINES.

The Schedule referred to in these Letters Patent and making part of the same.

Be it known that I, DEDRICK JORDAN, of Charlestown, in the county of Middlesex, and State of Massachusetts, have invented a new and useful improvement in Cutter-Guides for Wood-Moulding Machines, of which the following is a full, clear, and exact description, reference being had to the accompanying drawings, making a part of this specification, in which—

Figure 1 represents an elevation of the cutter-guide, containing my improvements.

Figure 2 is a section of the same, showing the knives and adjusting devices.

Figure 3 is a transverse section on the line x x of fig. 1.

Similar letters of reference indicate like parts in the several figures.

The object of my invention is to provide a means for gauging the thickness of a shaving at any desirable portion of the edge of the cutter, and also a means for readily adjusting the gauge collar to the cutters; and the invention consists in constructing the gauge collar with an outwardly projecting flange at its lower edge, by which the shaving is gauged; and also in the use of an adjustable collar, in connection with a tightening and a regulating nut, so arranged as to admit of the gauge collar being raised or lowered to adjust it to any desired position in relation to the cutters.

My invention is designed as an improvement upon a rotary cutter for which a patent was granted to J. P. Grosvenor, on May 28, 1858.

Referring to the drawings, s represents a vertical spindle or arbor, to the lower end of which is attached a base-piece, o , which serves as a support to the cutters and collars above. On the base-piece o rest the cutters n n , which fit in corresponding grooves in the same, and also in grooves in the collar m above. k k represent knives, which fit in corresponding grooves formed respectively in the collars l m , as shown in fig. 2, and over the collar l are fitted, in a similar manner, the cutters i i , which project through openings in the cutter-guide a , and are surmounted by the collar h . The cutters, of which there may be a series, according to the nature of the moulding required, are of curved form, as shown in fig. 3, and are fitted in corresponding grooves in the several collars. By curving the cutters a more direct cut can be made upon the stuff than by the usual straight knife, and they are also more easily adjusted to the work. The straight knife, when projected considerably from the guide, has rather a scraping effect, whereas the curved cutter is better adapted to shave the material. a represents the cutter-guide, which is formed with a shoulder, a' , that rests upon a nut, c , which latter screws upon the cylinder e . The cylinder e is screw-threaded on its outer surface, and is fitted to move freely on the spindle s . A retaining-nut, d , screws upon the cylinder e , and rests upon the upper portion of the cutter-guide a . The lower portion of the cutter-guide a is formed with an outwardly projecting edge b , as shown in fig. 2, by means of which, as the guide is adjusted higher or lower, the thickness of the shaving may be readily gauged at any desired portion of the edge of the cutters k . The projection b serves also as a protection to the workmen, as it prevents the stuff from being unduly acted upon by the rapid rotation of the cutters, which frequently occasions serious accidents. The cutter-guide a is adjusted to the cutters by first removing the retaining-nut d . The guide a being then lifted off, the nut c is screwed up or down on the threaded cylinder e , which admits of the knives or cutters being raised or lowered. The guide a is then replaced and secured in position on the nut c by the nut d . n is a nut, which serves to hold the parts together on the spindle. The collar m is also constructed with an outwardly projecting flange m' , as shown, for the purpose of gauging the shaving, and also serving as a guide.

I do not claim a rotary cutter-guide, as I am aware such has been used. But what I do claim, and desire to secure by Letters Patent, is—

The combination of the cutter-guide a , constructed with the flange b , the cylinder e , and the adjustable and retaining-nuts c d , as and for the purpose specified.

In testimony whereof I have signed my name to this specification in the presence of two subscribing witnesses.

DEDRICK JORDAN.
